UNITED STATES PATENT OFFICE

JAMES F. NEWTON, OF PHILADELPHIA, PENNSYLVANIA, ASSIGNOR TO PRIMROSE TAPESTRY CO., INC., OF PHILADELPHIA, PENNSYLVANIA, A CORPORATION OF PENNSYLVANIA

DESIGN FOR A TEXTILE FABRIC

Application filed November 3, 1927. Serial No. 23,984. Term of patent 7 years.

To all whom it may concern:

Be it known that I, JAMES F. NEWTON, a citizen of the United States, residing at Philadelphia, in the county of Philadelphia and State of Pennsylvania, have invented a new, original, and ornamental Design for Textile Fabric, of which the following is a specification, reference being had to the accompanying drawing, forming a part thereof.

The figure is a plan view of a piece of textile fabric showing one half of the design.

I claim:

The ornamental design for a textile fabric, as shown and described.

JAMES F. NEWTON.
